(57) CLAIM

The ornamental design for a block game, as shown and described.

DESCRIPTION

FIG. 1 is a perspective view of the block game showing our new design;

FIG. 2 is a front view of FIG. 1, the back view being a mirror image thereof;

FIG. 3 is a right-side view of FIG. 1, the left side view being a mirror image thereof;

FIG. 4 is a top view of FIG. 1;

FIG. 5 is a bottom view of FIG. 1;

FIG. 6 is a perspective view of the block game shown in FIG. 1, wherein the blocks are arranged in a different order; FIG. 7 is a front view of FIG. 6, the back view being a mirror image thereof;

FIG. 8 is a right-side view of FIG. 6, the left side view being a mirror image thereof;

FIG. 9 is top view of FIG. 6;

FIG. 10 is a bottom view of FIG. 6;

FIG. 11 is a perspective view of the block game shown in FIG. 1, wherein the blocks are arranged in a different order; FIG. 12 is a right-side view of FIG. 11;

FIG. 13 is a front view of FIG. 11;

FIG. 14 is a left side view of FIG. 11;

FIG. 15 is a back view of FIG. 11;

FIG. 16 is a top view of FIG. 1;

FIG. 17 is a bottom view of FIG. 1;

FIG. 18 is a perspective view showing the three varieties of block components within the block game;

FIG. 19 is a left side view of FIG. 18, the right-side view being identical thereto;

FIG. 20 is a top view of the three block components in FIG. 18, the bottom view being identical thereto; and,

FIG. 21 is a front view of FIG. 18, the back being identical thereto.

The horizontal hash lines represent the color blue, the vertical hash lines represent the color red, and the portions with no hash lines represent the color white in the claimed block game.

1 Claim, 21 Drawing Sheets
